DESIGN FOR A LIGHTING FIXTURE

Milton S. Greenwald, Los Angeles, Calif.

Application September 20, 1944, Serial No. 115,374

Term of patent 7 years

(Cl. D48—4)

To all whom it may concern:

Be it known that I, Milton S. Greenwald, a citizen of the United States, residing at Los Angeles, county of Los Angeles, in the State of California, have invented a new, original, and ornamental Design for Lighting Fixture, of which the following is a specification, reference being had to the accompanying drawing, forming part thereof.

Fig. 1 is a perspective view illustrating the top, side and front of the lighting fixture showing my design.

Fig. 2 is a bottom view of the fixture embodying my design.

Fig. 3 is a section along a transverse plane 3—3 of Fig. 1, to facilitate understanding of Figs. 1 and 2.

I claim:

The ornamental design for a lighting fixture, substantially as shown.

MILTON S. GREENWALD.
